HAROLD L. BLANCHARD, OF NORTHBIDGE, AND WALTER H. WAKEFIELD, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

DEVICE TO PREVENT ROTATION OF BOBBINS.

Application filed March 26, 1924. Serial No. 702,169.

To all whom it may concern:

Be it known that we, HAROLD L. BLANCHARD and WALTER H. WAKEFIELD, citizens of the United States, residing at Northbridge and Worcester, respectively, in the county of Worcester and State of Massachusetts, have invented a new and useful Device to Prevent Rotation of Bobbins, of which the following is a specification.

10 This invention relates to improvements in weft replenishing mechanism for looms and more particularly to means for preventing the rolling of bobbins on their axes in such mechanism.

15 In the usual type of multi-color weft replenishing mechanism the bobbins are arranged in vertical compartments according to color or other distinguishing characteristic and are moved by suitable discharge mechanism to transfer position. It has been found when the filling is fine, causing the bobbins to remain in the replenishing mechanism for a considerable length of time before transfer, that the ends which extend 20 to the thread holder are likely to be entangled with each other due to the rolling of the bobbins on their axes.

25 The type of bobbin usually employed in weft replenishing mechanisms has the butt or head thereof provided with a plurality of open rings which are snapped onto the heads of the bobbins in such a way as to leave the ends of the ring spaced, thus forming on the bobbin a slight depression or notch for each ring. The rings are so placed 30 that the notches are distributed around the head of the bobbin so that no two are in alignment. It is an important object of our invention to provide means for utilizing 35 the notches defined by the ends of the rings to prevent rotation of the bobbins. Accordingly, we have provided each compartment with a wall equipped with resilient detents so placed as to fit into one or another of 40 the notches formed on each bobbin to prevent objectionable movements of the bobbins. The detents are preferably withdrawn at the time of indication of weft exhaustion 45 to permit the bobbins to descend as the operation of the replenishing mechanism 50 requires.

It is another object of our invention to prevent rolling of the bobbins by providing each compartment with a wall movable

throughout its length laterally with respect 55 to the bobbins into engagement therewith, such mechanism being moved by the replenishing mechanism at indication of weft exhaustion to release the bobbins.

A still further object of our invention is 60 to provide each compartment of a weft replenishing mechanism of the type mentioned with a wall which shall be movable positively both to engage and to release the bobbins and so arranged that the wall is 65 held positively in both positions.

With these and other objects in view which will appear as the description proceeds, our invention resides in the combination and arrangement of parts hereinafter 70 described and set forth in the claims.

In the accompanying drawing, wherein we have shown one form of our invention,

Fig. 1 is an end elevation of a weft replenishing mechanism employing our invention as viewed from the center of the loom to which it is applied, 75

Fig. 2 is a vertical section taken on line 2—2 of Fig. 1,

Fig. 3 is a horizontal section taken on line 3—3 of Fig. 1,

Fig. 4 is a fragmentary section taken on line 4—4 of Fig. 3,

Fig. 5 is a perspective view of one of the movable walls embodied in our invention, 85 and

Fig. 6 is a fragmentary view showing on an enlarged scale a portion of the resilient detent member.

In carrying out our invention we provide 90 a weft replenishing mechanism having a frame 10 supported by means of a foot 11 bolted or otherwise secured to the loom side and having formed therewith a plurality of flanges 12, 13, 14 and 15, respectively, 95 each of which forms one wall of a bobbin compartment. Mounted for vertical movement on the frame 10 are slides 16, 17, 18 and 19, respectively, which are similar to each other and are each provided with upper 100 lugs 20 and lower lugs 21. A longitudinally and angularly movable rod 22 under control of the box mechanism (not shown) has secured thereto a finger for each pair of vertical slides, one finger being shown in Fig. 105 2 and indicated at 23. The rod 22 is moved lengthwise as the boxes change so that the fingers thereon will be in operative relation

with the vertical slide corresponding to the active shuttle. Said rod 22 is given an angular motion to lift the fingers at indication of weft exhaustion and is given a periodic 5 downward motion every two picks of the loom.

At weft exhaustion the slide corresponding to the indicating shuttle is raised to rock the corresponding cradle (not shown) at the 10 bottom of the compartment, the effect of which is to cause the lowermost bobbin to enter the cradle preparatory to its second motion toward transfer position. The matter thus far described is old in the art and 15 for a more complete showing and description thereof, reference may be had to Patent No. 1,030,748.

In carrying out our invention we provide each of the vertical slides 16, 17, 18 and 20 19 with a pair of slotted extensions which cooperate with extensions on the corresponding movable wall, and inasmuch as the slides and associated movable walls constitute units which are substantially the same for 25 each compartment, a description will be given of but a single unit, it being understood that this description applies to all the units. Referring to Figs. 1 and 2 it will be seen that slide 17 is provided with an upper 30 extension 40 and a lower extension 41 from which extend pins 42 and 43, respectively. Associated with the slide 17 is a wall 44 which is substantially parallel to wall or flange 13 and has offset therefrom upper 35 and lower ears 45 and 46, respectively. These ears are provided with slots 47 and 48, respectively, which receive the pins 42 and 43, respectively. The upper portion of the lower ear is provided with a horizontal 40 slot 49 which receives a pin 50 extending from a stationary part of the frame 10 and serves to guide the wall 44 so that the same is held against vertical motion and can move in a horizontal direction only.

45 The face of wall 40 adjacent wall 12 has secured thereto by rivets or other fastening devices 51 a thin sheet of spring steel 52 which has struck up therefrom resilient fingers 53 which are formed with detents 54 as shown more particularly in Fig. 4. These 50 detents extend away from the adjacent face of the wall 44 and are arranged substantially as shown in Fig. 2, the fingers being located in groups of three which are spaced 55 a distance substantially equal to the diameter of the butts of the bobbins.

In the operation of our invention the slides are normally down and the walls 44 are held toward the bobbins in their respective compartments so that one detent of each group is in position to enter the notch which is in alignment with the group of detents. At indication of substantial 60 weft exhaustion the rod 22 will be given an angular motion to move the fingers thereof 65

upwardly to raise the slide corresponding to the indicating shuttle and the corresponding wall 44 will be moved away from the bobbins through the action of pins 42 and 43 and slots 47 and 48, respectively. Which ever slide is raised will remain in such position with the corresponding bobbins released until transfer is about to take place, at which time the slide will be lowered, as described in the aforesaid Patent No. 75 1,030,748 and the associated wall 44 will again be moved toward the bobbins previously released. As the bobbins descend they are likely to take such positions that none of the notches formed by the rings will 80 be opposite the detents of the corresponding resilient fingers. If under these conditions the pressure of the detents against the rings does not prevent rotation of the bobbins, the latter will roll until one or another of the 85 notches on each bobbin will appear opposite a detent. Thereupon the detent will enter the notch and further rotation of the bobbin will be prevented. Since the bobbins have three rings which are evenly spaced, 90 it will be seen that a one-third rotation will suffice to bring a notched detent into co-operative relationship.

It will be seen from the foregoing that we have provided a weft replenishing 95 mechanism wherein each wall is provided with resilient fingers terminating in detents so placed as to be in position to enter at least one of the notches defined by the ends of the rings of each bobbin and that the entry of a detent into one of the notches will effectively prevent rotation of the corresponding bobbin. The wall has been shown as provided with groups of detents, 100 each group containing three fingers co-operating with notches formed by the adjacent ends of the rings with which the heads of the bobbins are fitted, but we do not wish to be limited to this particular construction 105 as our invention is equally applicable when a different number of detents is employed and when they may be operatively related to other styles of notches than those shown in the drawing. Also, it will be seen that we have provided a wall movable positively 110 either to restrain rotation of the bobbins or release the same so that they will be free to fall as the requirements of the replenishing mechanism demand and that the wall is acted upon at a plurality of points throughout its length so that it is moved bodily toward the bobbins.

In order to hold the walls 44 against transverse displacement we provide retainers 60 screwed to the frame 10 as at 61 and overlapping the lower ears 46. These retainers are spaced from the frame 10 sufficiently to permit free motion of said ears 46.

Having thus described our invention it is apparent that changes and modifications 130

may be made therein by those skilled in the art without departing from the spirit and scope of the invention and we do not wish to be limited to the details herein disclosed,
5 but what we claim is:

1. In a weft replenishing mechanism for looms, a fixed wall, a movable wall under control of the replenishing mechanism and forming with the fixed wall a compartment
10 for bobbins, and resilient detents carried by the movable wall to enter notches formed in the bobbins to restrain rotation thereof.
2. In a loom, a weft replenishing mechanism, a compartment to receive a plurality
15 of bobbins which descend by gravity in said

compartment toward transfer position, the bobbins being loosely held in the compartment and having notches on the cylindrical portions thereof, and plurality of independently yieldable devices normally entering 20 the notches to restrain rotation of the bobbins and movable under control of the replenishing mechanism at the time of transfer away from the notches to release the bobbins and permit them to fall unresisted 25 by said devices toward transfer position.

In testimony whereof we have hereunto affixed our signatures.

HAROLD L. BLANCHARD.
WALTER H. WAKEFIELD.
